WILLARD IRVING TWOMBLY, OF NEWARK, NEW JERSEY, ASSIGNOR TO ACME ACCESSORIES CORPORATION, OF NEW YORK, N. Y., A CORPORATION OF NEW YORK.

LIQUID-FEEDING MEANS AND PUMP.

Application filed October 20, 1917, Serial No. 197,589. Renewed October 12, 1921. Serial No. 507,357.

To all whom it may concern:

Be it known that I, WILLARD IRVING TWOMBLY, a citizen of the United States, and a resident of Newark, in the county of 5 Essex and State of New Jersey, have invented certain new and useful Improvements in Liquid-Feeding Means and Pumps, of which the following is a specification.

This invention relates to liquid, such as 10 liquid fuel or gasolene, feeding means to draw fuel from a source of supply or a tank and deliver it to the intake of an engine, such as the carburetor of an internal combustion engine, and it is the object of the 15 invention to provide improved liquid feeding means operable from the movements of the engine, which means are simple and cheap in construction and efficient in operation.

20 Heretofore in apparatus of this character it has been the practice to connect means to the manifold intake of an engine and to utilize the suction of the piston of the engine to create a vacuum to lift the fuel from a 25 tank and deliver it to a reservoir from which it was fed by gravity, or to connect a pump chamber to the manifold of the engine the pump being actuated by the suction of the engine during the fuel intake stroke of 30 the piston to draw the fuel from a tank and deliver it to a reservoir from which it is fed by gravity to the carburetor.

35 One object of the invention is to provide means connected directly to the cylinder of the engine and operable by the varying pressures in the engine cylinder, such as during the power and suction strokes of the piston, to draw the fuel from a tank and deliver it to the engine.

40 It is a further object of the invention to provide liquid feeding means of this character including a pumping mechanism having a reciprocable piston, said pumping mechanism being interposed between the fuel 45 tank and the engine, the piston of the pumping mechanism operating to separate the pump cylinder into a motive chamber and a pump chamber, the motive chamber being connected to the combustion chamber of 50 the engine and the piston reciprocated through the varying pressures in the combustion chamber, such as during the power and suction strokes of the engine piston, and the pumping chamber having an inlet con-

nected to the tank and an outlet whereby as 55 the piston is reciprocated liquid is drawn from the tank through the inlet of the pump chamber and delivered from the outlet of the pump chamber.

A further object of the invention is to provide means in which the pumping mechanism 60 normally operates to shut off communication between the engine and tank and between the pump and tank, and operable to open communication between the tank and engine 65 when the piston is reciprocated.

Another object of the invention is to provide liquid feeding means of this character in which the outlet of the pump chamber is 70 connected and the liquid delivered to a reservoir which is connected to the fuel intake means of the engine, and to provide means whereby the liquid level is controlled and controls the actuation of the pumping mechanism to draw and deliver liquid from the 75 tank.

Other objects and advantages will herein-after appear.

In the drawings accompanying and forming a part of this specification Figure 1 is 80 a diagrammatic view showing an embodiment of my invention applied to a motor vehicle utilized to lift gasolene from a tank and deliver it to the carburetor of an engine, the tank being located at a point below the 85 carburetor.

Figure 2 is a sectional side elevation of an embodiment of a pumping mechanism combined with a reservoir for use in connection with my improved fuel or gasolene feeding 90 means.

Figure 3 is a sectional side elevation illustrating a modified form of pumping mechanism combined with a reservoir for use in connection with my improved fuel or gas- 95 olene feeding means.

Figure 4 is a cross sectional view of the pumping mechanism taken substantially on the line 4-4 of Figure 3 and looking in the direction of the arrow.

Figure 5 is a sectional side elevation of a modified pumping mechanism combined with a reservoir for use in connection with my improved fuel or gasolene feeding means.

Figure 6 is a plan view of the pumping 105 mechanism shown in Figure 5 with the cover for the reservoir removed.

Figure 7 is a cross sectional view taken

substantially on the line 7—7 of Figure 5 looking in the direction of the arrow; and

Figure 8 is a cross sectional end elevation of a further modification of a combined 5 pumping mechanism and reservoir for use in connection with my improved fuel or gasoline feeding means.

In Figure 1 of the drawings I have shown 10 an embodiment of my invention applied as a fuel or gasoline feed in connection with a motor vehicle, the motive power of which is an internal combustion engine 9 to which is connected a carburetor 10 by a manifold 11, and a fuel or gasoline supply tank 12 located at the rear of the vehicle at a point 15 below the carburetor, with my improved means (designated in a general way by P) to draw the fuel from the tank and deliver it to the carburetor of the intake of the engine in position between said tank and carburetor, the tank being connected thereto by a pipe 13 and the carburetor by a pipe 14; said means to draw fuel from the tank and deliver it to the carburetor is connected 20 by a pipe 15 to the combustion chamber of the engine, such as the opening for the priming cup for the engine, as shown at 16.

The means to draw and deliver the fuel from the tank to the carburetor or engine is 25 operable by the varying pressures in the combustion chamber of the engine, such as during the power and compression strokes, or the suction and exhaust strokes, of the engine piston, and in the form thereof shown 30 in Figure 2 includes, preferably in combination with a high level reservoir 29, a cylinder 17 in which there is mounted a reciprocable piston 18, said piston separating the cylinder into a motive chamber 19 and a pump 35 chamber 20. The motive chamber has a port 23 in a removable end 21 for the cylinder 17 and to the threaded projection 22 of which closure 21 the pipe 15 connected to the engine is connected whereby the motive 40 chamber has a conduit affording an open 45 connection with the combustion chamber of an engine cylinder. The pump chamber 20 has an inlet 24 connected through a coupling and the pipe 13 with the tank 12, the inlet 50 being normally closed by a gravity seated valve 26 opening into and closing outward from the pump chamber 20. The pump chamber has an outlet consisting of a series 55 of circumferentially disposed ports 27 extending diagonally through a flanged portion of the cylinder leading into a reservoir 29. The outlets of the ports are located in a beveled portion 30 forming a seat for a valve 31 to close the ports, said valve being 60 in the form of a sleeve slidably mounted upon the cylinder 17 and having a laterally flaring portion to correspond with the beveled portion 30. The valve opens into and closes outward from the reservoir and is 65 normally maintained yieldingly closed when

the liquid level in the reservoir is below a predetermined level by the weight of a float 32 embracing the cylinder 17 and movable longitudinally thereof and an intermediate spring 33 fixed, as by soldering, to the float 70 and valve. The reservoir consists of a cylindrical sheet metal receptacle, in which the pumping mechanism is axially located, said reservoir having an outlet 34 to which the pipe 14 leading to the carburetor is connected, and open at the top with the upper end flaring outward as shown at 35. The reservoir is closed by a cover 36 having an annular flange 37 to engage within the flaring portion 35. The cover has a central 80 opening through which the cylinder 17 extends and the cover flange 37 is caused to forcibly engage the flaring end 35 of the reservoir to prevent leakage by the splashing of the fuel in the reservoir by the 85 screw closure or cap 21 on cylinder 17. Thus the pump cylinder serves the functions of a centering stud and as a tension bolt to clamp the cover on the reservoir the end of the cylinder 17 to which the cover 90 may be connected. A port 38 of small area may be provided to permit of the escape of air from and entrance of air to the reservoir. The piston 18 has the usual annular oil grooves 39 and carries a packing ring 40 95 of suitable material, said ring being clamped between the piston and a flanged clamping nut 41 threaded onto a projection 42 of the piston, the flange having a loose fit in the cylinder and providing a recess between said 100 flange and the piston for the engagement of the piston packing for a purpose to be hereinafter described. The piston 18 is yieldingly maintained toward the outermost end of the motive chamber by a spring 43, 105 a spring bumper 44 being interposed between the flange of the piston nut 41 and the closure end 21 for the motive chamber to prevent the piston striking against the end of said chamber and making a clicking or 110 knocking noise.

It will be noted that the report 23 is of extremely small diameter as compared with the volume of the pump chamber but it will be understood that this may be varied if 115 desired, as for instance, to vary the power or capacity of the pump.

In the operation of the pumping mechanism during the compression strokes of the piston of the engine due to the connection 120 15 of the motive chamber of the cylinder 17 with the combustion chamber of the engine cylinder such pressure will be exerted on the end of the piston nut 41, a portion of such pressure due to the loose fit of the nut 125 25 flange entering the space between the flange and piston proper expanding the packing 40 and moving the piston against the action of the spring 43, the expansion of the packing ring also preventing the passage of such 130

pressure to the pump chamber. This movement of the piston will unseat the valve 31 to open communication between the pump chamber and the reservoir. During the suction strokes of the engine piston with the consequent reduction of the pressure in the connection 15 and in the motive chamber the spring 43 will move the piston toward the outer end of the motive chamber, the valve 31 having automatically seated by gravity such movement of the piston 18 will create a vacuum in the pump chamber unseating the valve 26 and drawing the fuel from the tank 12 through the connection 13 thereof with the pump chamber into the latter. This latter movement of the piston 18 will also be facilitated during the suction stroke of the piston of the engine by the creation of a vacuum in the motive chamber. The pipe 14 leading to the carburetor is connected to the reservoir 29 and the fuel from the reservoir to the carburetor is fed by gravity through said pipe. If used for feeding gasoline to the carburetor of an ordinary automobile engine, it would be extremely difficult to proportion the parts so that the continuous operation of the pumping mechanism would not flood the reservoir 29 and to control the fuel level therein the float 32 is provided. As the fuel level in the reservoir rises the buoyancy of the float will cause it to rise and move upward. This motion may be used to control the pump in any desired way. As shown in Figure 2, the float being connected through the spring 33 with the valve 31 will lift and unseat the valve 31 maintaining the valve open until the fuel level is lowered, the movement of the piston 18 while the valve 31 is open alternately drawing the fuel from and discharging it into the reservoir until such time as the fuel level permits the float to again assume a position with the valve 31 closed.

It will be noted that the piston 18 at all times shuts off communication between the combustion chamber of the engine cylinder and the tank, and that communication between the intake of the engine and the tank is shut off from the reservoir by the valves 26 and 31 for the inlet and outlet of the pump chamber, and that communication between the tank and intake of the engine is only during the operation of the pumping mechanism.

The reciprocations of the piston 18 synchronizes with the suction and compression strokes of the engine piston, and the stroke of the piston 18 is regulated in accordance with the pressure in the engine cylinder. For instance, should the throttle valve for the fuel intake of the engine be closed with consequent low pressures in the engine cylinder there will be a low pressure in the motive chamber of the cylinder 17 and a

short motion or stroke of the piston 18, and as the throttle valve for the engine intake is opened with the consequent increase of pressures in the engine cylinder there will be a corresponding increase of the pressures 70 in the motive chamber of the cylinder 17 and a longer stroke imparted to the piston 18.

It will be evident, however, that in operation of an automobile engine, the explosions 75 may vary from say 3 or 4 per second when idling up to 40 or 50 or more per second at maximum speed. Hence a spring which is yielding enough to permit the above described operation of the piston under close-throttle, low-pressure conditions will function somewhat differently when the engine is operating at high speed. This is because at high speeds, there is as much or more work to be done by the spring actuated return stroke of the piston and there is much less time to do it in. Hence the return stroke may be cut short by a succeeding explosive pressure before the piston gets back to initial position.

Moreover, while the extreme constriction of the inlet passage as shown in the drawings, serves to moderate on the pump piston, the violence of the engine explosions, it also tends to average up the low pressures 90 as well as to average down the high pressures, and this tendency becomes more pronounced with increasing speeds of the engine. Hence though the pressures in the engine cylinder continue to alternate between 95 pronounced vacuum and high pressure even at high speeds, the pressures on the pump piston will become pulsating, that is, they are above atmosphere even during the vacuum strokes of the engine. This pulsating 100 excess pressure at high speeds tends to force the pump piston toward the spring thereby compressing the spring until a position is reached where the spring is under a continuous minimum compression equal to the 105 continuous minimum pressure in the motive chamber.

The piston continues to reciprocate in response to the variations of pressure, and the length of the stroke may be approximately 110 the same or may be less, but the range of the stroke is shifted enough to make the spring return strokes more powerful and therefore quicker acting.

Making the spring 43 of ample length 115 and providing a long clearance or pumping space in the cylinder, as shown in the drawings, affords a considerable range for the above described shift of position of the stroke of the piston, with the corresponding 120 increase of spring stiffness. It is one good method of rendering the device automatically self-accommodating for the wide range of alternating and pulsating pressures due 125 to the constricted inlet during the widely 130

varying speeds practically necessary in the 5 operation of automobile and similar internal combustion engines. For a wide range of speeds the length of the stroke will be determined by the pulsating differences of pressure during each cycle of explosion, exhaust, suction and compression in the engine, independently of the amounts of said pressures, said changes in the amounts being taken 10 care of by the automatic shift of the position of the stroke to the extent necessary to get a counterbalancing back pressure of the spring.

The spring 44 on the opposite end of the 15 piston, is of shorter length and shorter range of action than spring 43. It functions only when conditions are such as to permit complete return stroke of the piston on each suction stroke of the engine and this, as will 20 be evident, is at the lower engine speeds and pressures, particularly at times when the speeds and pressures are low enough for establishing a vacuum, or below-atmosphere, pressure in the motive chamber of the pump 25 during each suction stroke of the engine. At such times the spring 44 is compressed by the suction stroke of the piston. Then, as soon as the suction is relieved, the expansion of spring 44 initiates and assists the 30 subsequent expansion stroke. In this way the short spring 44 acts during times of alternating suction and pressure on the piston, in a manner somewhat analogous to the action of spring 44 during times of continuous 35 pulsating pressure. This functioning of bumper spring 44 is more easily visualized where a longer bumper spring is used, as at 57, Figures 3, 5 and 8.

While the float controlled inlet shown 40 herein is one means for governing the pumping of the liquid, it will be evident that the advantageous features of construction of the reservoir and arrangement of pump cylinder as well as the liquid intake and motive 45 pressure inlet may be utilized where governing of the pump is not desired, or where other methods of governing are employed, as for instance, those shown in Figures 5 and 8 of this application.

It will be noted that in the specific governing arrangement shown herein the float 32, 50 spring 33 and outlet valve 31 are means whereby the pump is rendered first ineffective and then inoperative, by gradual lifting 55 of the outlet valve out of range of the outlet passages as the float rises to the uppermost position. Conversely as the liquid is drawn off and the level lowers, the valve seats upon the pump outlets and presses 60 more and more heavily thereon until, in full normal operation, the entire weight of the float may rest upon the valve. Thus in normal operation the outlet will be of much higher resistance to outflow of fluid than 65 the inlet is to inflow. The purpose and re-

sult of this is explained hereafter in connection with Figure 5.

In the form of pumping mechanism shown in Figures 3 and 4 the piston cylinder 17 extends in a horizontal plane the piston 18 70 also separating the cylinder into the motive chamber 19 and pump chamber 20. The inlet connection 23 of the motive chamber with the engine cylinder is in a cap 45 closing the end of the motive 75 chamber. The inlet 24 for the pump chamber is in the lateral wall of the pump chamber and communicates with a port in a coupling 46 to connect the inlet with the pipe 13 leading to the tank 12, said port 80 normally being closed by a gravity seated valve 47 co-operating with a valve seat in the coupling 46, said valve opening into and closing outward from the pump chamber 20. The outlet 27 of the pump chamber is 85 in the lateral wall of the pump chamber and a boss extending laterally therefrom and is normally closed by a valve 48 closing into and opening outward from the pump chamber 20. The valve 48 has a tubular 90 portion to engage in the outlet and a beveled portion 49 to seat in a correspondingly shaped portion of the outlet, the tubular portion of the valve having a longitudinal flute 50 below the beveled portion 49 to 95 facilitate the discharge of the fuel from the pumping chamber without withdrawing the tubular portion of the valve from the outlet. The outlet 27 leads into a reservoir 51 constructed integral with the cylinder 17, 100 and the reservoir has an open top closed by a cover 52 removably secured to the reservoir by a rod 53 threaded into a boss on the cylinder 17 and extending through the cover with a nut 54 engaging on the threaded end 105 of the rod projecting from the cover, and from which reservoir the fuel is delivered to the carburetor through the pipe 14 connected thereto. The piston is yieldingly maintained toward the outermost end of the 110 motive chamber 19 by a spring 56 one end of which spring abuts against the end of the pump chamber and the other end is seated in a sleeve portion of the piston, a spring bumper 57 being interposed between 115 the head of the piston and the end of the motive chamber to prevent the piston striking against the end of said chamber and making clicking and knocking noises.

The operation of the pumping mechanism 120 shown in Figures 3 and 4 is similar to the operation of the pumping mechanism shown in Figure 2. To control the fuel level in the reservoir 51 there is a float 60 in the reservoir carried at one end of a plate 61 supported by pivot points 62 at opposite sides of the plate at the end opposite to the float. A stem 63 on the valve 48 passes through an opening in the float supporting plate 61 and has lock nuts 64 on the free 125 130

end on the side of the plate opposite to the valve to prevent withdrawing of the stem from the plate opening, with a spring 65 coiled about the valve stem 63 between the 5 plate 61 and valve. As the fuel level rises in the reservoir the float will rise, thereby lifting the valve 48 from its seat and maintaining the valve open until the fuel level is lowered, the piston 18 while the valve 48 10 is open alternately drawing fuel from and discharging it into the reservoir until such time as the fuel level permits the float to again assume a position to engage with and be supported by a nut or abutment 66 on the 15 rod 53 and the valve 48 in closed position.

In the modification of the pumping mechanism shown in Figures 5 to 7 the pumping operation is similar to that described in connection with Figures 1 and 2 but the construction resembles that shown in Figures 20 3 and 4, the functioning of springs 56 and 57 being respectively similar to that described for springs 43 and 44. The connection 15, instead of being directly with the 25 motive chamber of the pumping mechanism is through ports 67 and 68 controlled by a valve 69. The outlet of the pump chamber 20 to the reservoir is through a port 70 in the cylindrical member 71 threaded into the 30 end of the pump chamber and a port 72 through the side walls of said cylindrical member and the pump chamber. The opening and closing of the ports 70 and 72 to 35 shut off communication between the pump chamber and the reservoir is controlled by a piston valve 73 slidably mounted in the cylindrical member 71 and normally maintained in position to shut off communication between the ports 70 and 72 by a spring 74. 40 The inlet and its valve and the outlet and its valve, have peculiarities which in combination contribute to the efficiency of the pump, especially when used for its preferred purpose as a fuel pump on an automobile 45 engine. As before explained, the explosion strokes in any one of the cylinders of an automobile engine will vary from say 3 or 4 per second for idling, up to say 40 or 50 or more per second, for high speed operation. Obviously, in such operation, any delay, even for a small fraction of a second, in the closing of the inlet valve will permit appreciable slip or backflow of liquid to 50 the tank.

55 It will be noted, however, that the inlet valve in Figure 5, as in all other figures of the drawing, is a free, gravity-seated ball. This is preferred because it is a simple and 60 very effective means of getting the quick, free, low-resistance opening of the inlet which is very desirable at all times, and particularly so when the supply pipe is empty and the gasoline must be lifted by first pumping air. But the ball form and absence of spring pressure which give the

quick, free, low-resistance opening, tend to make it slow-closing. Hence, the outlet port 72 through which the liquid is forced from the pump chamber into the reservoir is shown as being much smaller than the supply inlet 47; also the piston outlet valve is heavier and is more powerfully forced to closed position by employing the spring 74. The small size of the outlet port and the spring pressure on the valve both contribute to making the outlet of much higher resistance than the inlet. With such back-pressure on the outlet, the high speed movement of the piston under the explosive pressure from the engine, takes effect on incompressible liquid and instantly piles up a sufficient back pressure on the inlet valve to force it tight down on its seat at the very beginning of the expelling stroke of the piston. 80

A similar effect is obtained in other forms of the device shown herein. For instance, in Figure 2 when the pump is in full normal operation with the weight of the float 32 transmitted through spring 33 to the outlet valve, the outlet is throttled so as to be of considerably higher resistance than the inlet. Hence the expelling stroke of the piston can pile up the required pressure for instantly seating outlet valve 26. Similarly, 95 in Figure 3, when the float 60 is in the lowermost position, its weight is transmitted through spring 65 to outlet valve 49, thereby throttling the outlet and producing the required resistance to outflow of the liquid. In Figure 8, described hereafter, the inlet and outlet passages and valves are of the same size but the inlet ball 81 is seated only by gravity while the outlet ball 83 is continuously spring pressed downward, thereby 100 making the outlet resistance obviously much greater than the inlet resistance. 105

The fuel level in the reservoir is controlled by a float 75 in the reservoir connected by a rod 76 to the valve 69, whereby as the fuel in the reservoir reaches a predetermined level in the reservoir and the float rises to the position shown in lower dotted line position in Figure 7 the valve will be operated through the float to throttle communication between the engine cylinder and the motive chamber of the cylinder 17 and will be entirely shut off as it assumes the upper dotted line position, and thereby prevent the operation of the piston 18 during the movements of the engine piston. To indicate the extent of the movement of the piston 18 during operation, and to also permit of manual operation of the piston, a rod 77 secured at one end in the piston 18 extends through 110 and slidably engages in the closure 45. The reservoir has a suitable outlet connected to the carburetor by the pipe 14. In the form shown in the drawings the casing of valve 69 is integral with the pump cylinder 115 120 125 130

and in manufacture of the device the passage 68 is drilled downward through the small hole shown in the top of the valve casing. This hole may be plugged but preferably 5 it is left open to permit access of a minute quantity of gasoline to slightly lubricate the valve 69.

In the modification shown in Figure 8 the 10 construction and operation of the pumping mechanism and the connection thereof with the engine cylinder is the same as in Figures 3 and 4 except that the piston 18 moves in a vertical direction instead of in a horizontal plane. The pump chamber 20 15 of the cylinder 17 is connected to the source of supply or tank 12 by the pipe 13 through a port 80 and communication between the pump chamber and tank is normally shut off by a gravity seated valve 81 opening 20 into and closing outward from the pump chamber. The fuel is discharged from the pump chamber to the reservoir 51 through a port 82 normally closed by a spring influenced valve 83 closing into and opening 25 outward from the pump chamber. The fuel level in the reservoir is controlled through a port 84 between the reservoir and the port 80 on the side of the valve 81 opposite to the pump chamber. This port 84 is normally 30 closed by a gravity seated valve 85 similar to the valve 48 in Figure 3 and the opening of which valve is controlled by a float 86 in the reservoir. The valve 85 has a stem 87 extending up through the float to 35 permit the float to have a sliding movement thereon and through a sleeve 88 on the end projecting from the float, said sleeve and stem extending through and being slidable in an opening in the cover of the reservoir, 40 a lock nut 89 on the stem retaining the sleeve in predetermined position on the stem. As the level of the fuel in the reservoir rises the float will move upward, as for instance from the full line to the dotted line position, when it will engage with the sleeve 88 and any further upward movement of the float will move the valve stem and valve 85 with it thereby unseating the valve and opening communication between the reservoir 45 51 and the port 80 and permitting the flow of the fuel from the reservoir to the tank until the fuel level again reaches a predetermined level in the reservoir and the port 84 is closed by the valve 85.

Having thus described my invention, I claim:

1. Fuel feeding means for internal combustion engines, comprising the combination with a liquid fuel tank and an internal 60 combustion engine, of means interposed between and connected to the engine and tank including a reciprocable piston of the same diameter throughout and of greater length as compared with its diameter operable by 65 the varying pressure of the engine motive

actuating fluid within the engine cylinder during the operation of the engine to draw and deliver liquid from the tank.

2. Fuel feeding means for internal combustion engines, comprising the combination with a liquid fuel tank and an internal combustion engine, of a cylinder connected to the tank and the combustion chamber of the engine and a reciprocable piston in said cylinder operable by the pressure of the 75 engine motive actuating fluid in the combustion chamber to draw and deliver liquid from the tank and means operable by the liquid delivered by the piston to control the actuation of the piston. 80

3. Fuel feeding means for internal combustion engines, comprising the combination with a liquid fuel tank and an internal combustion engine, of a reciprocable pump, the piston of which pump is a relatively 85 light shell or cup of greater length than the cross sectional dimensions thereof, said pump being connected to the tank and the cylinder of the engine and operating to shut off communication between the engine and tank, and operable by the compression and 90 expansion pressure of the engine motive actuating fluid in the engine cylinder, together with a long helical compression spring in the pumping chamber and having 95 a considerable portion of its length housed within said cup, to draw and deliver liquid from the tank, for the purpose specified.

4. In fuel feeding means for internal combustion engines, the combination with a 100 liquid fuel tank and an internal combustion engine, of a reciprocal piston pump having a check valve controlled inlet connected to the tank and a check valve controlled outlet at one side of the piston, and 105 connected to the engine at the opposite side of the piston, and operable by the motive actuating fluid of the engine during the compression and expansion of such fluid to draw and deliver liquid from the tank, and 110 means in the connection of the pump with the engine operable when the pump has delivered a predetermined quantity of liquid from the tank to shut off the motive actuating fluid of the engine from the pump, for 115 the purpose specified.

5. Fuel feeding means for internal combustion engines, comprising the combination with a liquid fuel tank and an internal combustion engine of a reservoir having an 120 outlet, a pump interposed between and connected to the engine and tank, said pump chamber having a check valve controlled outlet to the reservoir and a reciprocable piston operating to shut off communication between 125 the engine and tank, said piston being operable by the compression and expansion pressure of the engine motive actuating fluid in the cylinder of the engine to open communication between the pump and tank and draw 130

- liquid from the tank and deliver it from the pump outlet to the reservoir; and a valve in the connection of the pump and engine controlled by the liquid level in the reservoir 5 for the purpose specified.
6. Fuel feeding means for internal combustion engines, comprising the combination with a liquid fuel tank and an internal combustion engine, of a reservoir having an outlet, a pump having a reciprocable piston connected to the engine, said pump being connected with the engine cylinder at one side of the piston and having a check valve controlled inlet from the tank and a check valve controlled outlet to the reservoir, the variable pressure of the engine motive actuating fluid in the engine cylinder being operable to actuate the piston to draw the liquid from the tank through the inlet of the pump 10 and deliver the liquid through the outlet to the reservoir; a valve in the connection of the pump and engine; and a float in the reservoir to control the actuation of the valve, for the purpose specified.
- 15 7. Fuel feeding means for internal combustion engines, comprising the combination with an internal combustion engine and a fuel tank, of a pump cylinder connected to the engine, said cylinder having an inlet connected to the tank and an outlet, a reservoir connected to the outlet of the pump cylinder; a piston in the pump cylinder of greater length than the diameter thereof operable by the pressure of the engine motive actuating fluid in the engine cylinder to draw liquid from the tank to the pump chamber and deliver it to the reservoir; and means in the connection of the pump and engine operable to control the actuation of the pump piston by the engine motive actuating fluid and the drawing of the liquid from the tank, by the liquid level in the reservoir.
- 20 8. In fuel feeding means for internal combustion engines, the combination with an internal combustion engine and a fuel tank, a pumping mechanism including a pumping element operable by the motive actuating fluid of the engine to draw liquid from the tank and deliver the liquid to the reservoir; and means controlled by the liquid level in the reservoir operable to control the actuation of the pumping element for the purpose specified.
- 25 9. Fuel feeding means for internal combustion engines, comprising the combination with an internal combustion engine and a liquid fuel tank, of a reservoir; a cylinder; a piston separating said cylinder into a motive chamber connected to the engine cylinder to operate the piston through the pressure of the engine motive actuating fluid in the engine cylinder, and a pump chamber connected to the tank and reservoir, and a valve in the connection of the motive chamber and engine operable by the varying liquid levels in the reservoir to connect and disconnect the motive chamber from the engine for the purpose specified.
10. Fuel feeding means for internal combustion engines, comprising the combination with an internal combustion engine and a fuel tank, of a cylinder; a reciprocable piston of greater length as compared with its diameter engaging in and separating said cylinder into a pump chamber at one side of the piston having a check valve controlled inlet connected to the tank and a check valve controlled outlet, and a motive chamber at the opposite side of the piston connected to the engine cylinder, said piston being reciprocable by the pressure of the engine motive actuating fluid in the engine cylinder to draw fuel from the tank to the pump chamber and deliver it through the outlet of the pump chamber for the purpose specified.
- 15 11. Fuel feeding means for internal combustion engines, comprising the combination with an internal combustion engine and a fuel tank, of a cylinder, a reciprocable piston separating said cylinder into a pump chamber at one side of the piston having a check valve controlled inlet connected to the tank and a check valve controlled outlet, and a motive chamber at the opposite side of the piston connected to the engine cylinder; a reservoir connected to the outlet of the pump chamber; said piston being of greater length as compared with its cross sectional dimensions and being movable in one direction by the engine motive actuating fluid in the engine cylinder and by a spring in the opposite direction to draw fuel from the tank to the pump chamber and deliver it to the reservoir; and means including a rotary valve in the connection of the pump with the engine cylinder and a lever and float connected to one end of said valve within said reservoir and operating to rotate said valve to control the actuation of the pump when the fuel rises to a predetermined level in the reservoir.
- 20 12. Fuel feeding means for internal combustion engines, comprising the combination with an internal combustion engine and a liquid fuel tank, of a reservoir, a cylinder connected to the combustion chamber of the engine, tank, and reservoir; a reciprocable piston in said cylinder, said piston being yieldingly urged to its outermost position and adapted to be moved by the compression and expansion pressure of the engine motive actuating fluid in the combustion chamber of the engine against the action of said yielding means to draw fuel from the tank to the cylinder and means to control the actuation of the pump by the rise and fall of the liquid level in the reservoir, and for the purposes specified.
- 25 13. Fuel feeding means for internal com-

bustion engines, comprising the combination with an internal combustion engine and a liquid fuel tank, of a cylinder connected at one end to the combustion chamber of the engine and at the opposite end to the tank and the fuel intake means of the engine; a reciprocable piston in said cylinder; a spring to yieldingly maintain the piston in its outermost position, said piston being adapted 10 to be moved against the action of the spring by the motive actuating fluid in the combustion chamber of the fuel engine to draw fuel from the tank and deliver it to the intake of the engine and means controlled by the 15 volume of liquid delivered by the piston to control the actuation of the piston.

14. In fuel feeding means for internal combustion engines, the combination with an internal combustion engine, a carburetor 20 connected to the fuel intake of the engine, and a liquid fuel tank, of a cylinder; a reciprocable piston engaging in said cylinder separating the cylinder into a motive chamber at one end of the piston connected to the combustion chamber of the engine to reciprocate the piston by the motive actuating fluid of the engine, and a pump chamber at the opposite end of the piston having an inlet connected to the 25 tank and an outlet; a check valve for the inlet of the pump chamber opening into and closing outward from the pump chamber; a check valve for the outlet of the pump chamber closing into and opening outward 30 from the pump chamber; a reservoir connected to the outlet of the pump chamber and having an outlet connected to the carburetor to feed the fuel to the latter from the reservoir by gravity; and means controlled by the volume of liquid in the reservoir 35 operable to shut off the motive actuating fluid of the engine from the motive chamber of the cylinder, for the purpose specified.

45 15. Fuel feeding means for internal combustion engines, comprising the combination with an internal combustion engine and a liquid fuel tank, of a cylinder; a reciprocable piston in said cylinder separating the 50 cylinder into a motive chamber at one side of the piston and a pump chamber at the opposite side of the piston; a port in the motive chamber connected to the engine cylinder to actuate the piston by the motive 55 actuating fluid of the engine; an inlet to the pump chamber connected to the tank; a reservoir; an outlet from the pump chamber leading to the reservoir; a valve to control the port of the motive chamber to connect and disconnect said chamber from the engine cylinder; and a float in the reservoir to operate said valve in accordance with the liquid level in the reservoir and control the operation of the engine.

65 16. Fuel feeding means for internal com-

bustion engines, comprising the combination with an internal combustion engine and a liquid fuel tank, of a cylinder; a reciprocable piston in the cylinder separating the cylinder into a motive chamber at one end 70 of the piston connected to the combustion chamber of the engine cylinder to actuate the piston through the varying pressures in the combustion chamber, and a pump chamber at the opposite side of the piston 75 having an inlet connected to the tank and an outlet; and a valve for the port of the motive chamber operable to connect and disconnect said chamber from the combustion chamber for the purpose specified. 80

17. Fuel feeding means for internal combustion engines, comprising the combination with an internal combustion engine and a liquid fuel tank, of a cylinder; a reciprocable piston separating the cylinder into a 85 motive fluid chamber at one side of the piston connected to the engine cylinder, and a pump chamber at the opposite side of the piston having an inlet connected to the tank and an outlet; a spring to maintain said piston in its outermost position in the motive chamber; said piston being reciprocable against the action of the spring by the varying pressures in the engine cylinder; and manually operable means to reciprocate the 90 piston against the action of the spring for the purpose specified.

18. In fuel feeding means for internal combustion engines, the combination with an internal combustion engine and a liquid 100 fuel tank, of a cylinder connected at one end to the engine cylinder and at the opposite end having an inlet connected to the tank and an outlet; a reciprocable piston in the cylinder; a spring to urge said piston to a predetermined position in the cylinder 105 said piston being reciprocable against the action of the spring by the motive actuating fluid in the engine cylinder; and a stem connected to the piston extending to the exterior of the cylinder to manually reciprocate the piston against the action of the spring, for the purpose specified. 110

19. In fuel feeding means for internal combustion engines, the combination with 115 a liquid fuel tank and an internal combustion engine, of a reservoir; means connected to the tank and reservoir including a pumping element operable by the engine motive actuating medium in the engine cylinder to 120 lift the fuel tank from the tank and deliver it to the reservoir; and means operable when the fuel reaches a predetermined level in the reservoir to shut off said fuel lifting and delivering means from the engine for the 125 purpose specified.

20. In fuel feeding means for internal combustion engines, the combination with an engine and a liquid fuel tank, of a reservoir having an outlet; a pump including a non- 130

- return check valve and a pumping element connected to and actuated by the varying pressure of the engine motive actuating fluid in the engine cylinder; and means operable 5 when the fuel reaches a predetermined level in the reservoir to shut off the motive actuating fluid from the engine to the pump for the purpose specified.
21. In fuel feeding means for internal 10 combustion engines, the combination with an engine and a liquid fuel tank, of a reservoir having an outlet; a suction creating element connected to and operable by the varying pressure in the engine cylinder hav- 15 ing a suction inlet connected to the tank and a valved outlet into the reservoir to control the drawing of the fuel from the tank and the discharge of the same to the reservoir; and means operable when the fuel reaches a 20 predetermined level in the reservoir to shut off the suction creating means from the engine for the purpose specified.
22. In fuel feeding means for internal 25 combustion engines, the combination with an engine and a liquid fuel tank, of a reservoir having an outlet; suction creating means connected to and operable by the varying pressure in the engine cylinder having a suction inlet from the tank and a valved out- 30 let into the reservoir to control the drawing of the fuel from the tank and the discharge of the same to the reservoir; and a valve in the connection between the suction creating means and the engine operable by 35 the varying liquid level in the reservoir to connect the suction creating means to and disconnect the same from the engine for the purpose specified.
23. In fuel feeding means for internal 40 combustion engines, the combination with a liquid fuel tank, an engine and a carburetor connected to the fuel intake of the engine, of a reservoir independent of the carburetor and from which the fuel is fed by gravity 45 to the carburetor; a pump connected to and actuated by the engine motive actuating fluid in the engine cylinder and having a suction inlet from the fuel tank and a check valve controlled outlet into the reservoir; 50 and a valve in the connection of the pump with the engine cylinder operable through the variations in the liquid level in the reservoir to control the motive actuating fluid from the engine cylinder to the pump and thereby the actuation of the pump for the 55 purpose specified.
24. In fuel feeding means for internal 60 combustion engines, the combination with a liquid fuel tank, an engine and a carburetor connected to the fuel intake of the engine, of a reservoir from which the fuel is fed to the carburetor by gravity; a pump connected to and actuated by the compression and expansion pressure of the engine 65 motive actuating fluid in the engine cylin-
- der, said pump having a suction connection from the fuel tank and a check valve controlled outlet into the reservoir; a valve in the connection between the pump and engine; and a float in the reservoir connected 70 to the valve and adapted to operate the valve to connect the pump to and disconnect it from the engine in accordance with the varying liquid levels in the reservoir for the purpose specified.
25. In liquid feeding means for internal 75 combustion engine, the combination with an internal combustion engine and a liquid supply tank, of a conduit and pressure actuated pump interposed between the tank and 80 the intake of the engine; said pump including a cylinder and a piston to reciprocate in said cylinder and separating the cylinder into a pump chamber and a motive chamber; a port and conduit connecting the motive 85 chamber with the engine cylinder; a spring in the pump chamber yieldingly pressing said piston toward said port; a valve controlled inlet toward the pump, leading from the tank; a pump outlet leading toward said engine intake; and a non-return valve adapted 90 to check reverse flow of liquid through said outlet during the lifting strokes of said piston; said motive chamber port being constricted and said spring and pump chamber long, as and for the purpose described.
26. A variable-throttle, variable-speed internal combustion engine in combination with a pump for utilizing the alternating 95 vacuum and high pressure conditions in a combustion chamber of the engine throughout all variations of throttle opening and engine speed, said pump including a reciprocating piston element having two working heads, one in operative relation to the pump 100 chamber and the other in operative relation to a motive chamber; suitable non-return valves controlling flow of fluid into said pump chamber through an inlet and flow of fluid out of said chamber through an outlet; 105 a conduit connecting the motive chamber of the pump with the motive chamber of a cylinder of the engine, including an intermediate constricted passage whereby at low speeds of the engine the alternating vacuum and high pressure conditions of the engine cylinder produce similar but modified vacuum and pressure conditions in the motive chamber of the pump, and, at high engine speed, produce pulsating pressures higher 110 than atmospheric in said motive chamber of the pump; and means for applying to said piston a counterpressure increasing automatically and progressively with the increase of the minimum pressures in the motive cylinder of the pump due to increasing speed of the engine.
27. A variable-throttle, variable-speed internal combustion engine in combination with a pump for utilizing the alternating 115

- vacuum and high pressure conditions in a combustion chamber of the engine throughout all variations of throttle opening and engine speed, said pump including a reciprocating piston element having two working heads, one in operative relation to the pump chamber and the other in operative relation to a motive chamber; suitable non-return valves controlling flow of fluid into said pump chamber through an inlet and flow of fluid out of said chamber through an outlet; a conduit connecting the motive chamber of the pump with the motive chamber of a cylinder of the engine, including an intermediate constricted passage whereby at low speeds of the engine the alternating vacuum and high pressure conditions of the engine cylinder produce similar but modified vacuum and pressure conditions in the motive chamber of the pump, and, at high engine speed, produce pulsating pressures higher than atmospheric in said motive chamber of the pump; means permitting reciprocation of said pump piston by the alternating pressure and vacuum in the motive chamber of the pump when the engine is operating at low speed and automatically compensating for the increased continuous portion of the pressure during high speeds of the engine, when the pressure in the motive chamber of the pump becomes pulsating because of said constriction.
28. A variable-throttle, variable-speed internal combustion engine, in combination with a pump for utilizing the alternating vacuum and high pressure conditions in the combustion chamber of the cylinder of the engine to pump fluids, throughout all variations of throttle opening and engine speed, said pump including a reciprocating piston element having two working heads, one in operative relation to the pump chamber and the other in operative relation to a motive chamber; an inlet and non-return valve therefor controlling free, low-resistance flow of fluid into said pump chamber; an outlet and non-return valve therefor controlling a relatively high resistance flow of fluid out of said pump chamber; a conduit connecting the motive chamber of the pump with the combustion chamber of a cylinder of the engine whereby at low speeds of the engine the alternating vacuum and high pressure conditions of the engine cylinder produce modified vacuum and high pressure conditions in the motive chamber of the pump and, at high engine speed, produce pulsating pressures higher than atmosphere in the motive cylinder of the pump; a long spring at the pump end of the piston to oppose the expansion strokes and assist the return strokes; and a shorter spring at the motive end of the piston to oppose vacuum strokes and assist expansion strokes.
29. A variable-throttle, variable-speed internal combustion engine, in combination with a pump for utilizing the alternating vacuum and high pressure conditions in a combustion chamber of the engine throughout all variations of throttle opening and engine speed, said pump including a pressure actuated piston having two working heads, one in operative relation to the pump chamber and the other in operative relation to a motive chamber; a spring compressed by the pressure actuated stroke to force the return or suction stroke of the piston; an inlet and non-return valve therefor controlling free, low-resistance flow of fluid into said pump chamber; an outlet and non-return valve therefor controlling relatively high resistance flow of fluid out of said chamber; a conduit connecting the motive chamber of the pump with the combustion chamber of a cylinder of the engine.
30. A variable-throttle, variable-speed internal combustion engine in combination with a pump for utilizing the alternating vacuum and high pressure conditions in the combustion chamber of the cylinder of the engine to pump fluids throughout all variation of throttle opening and engine speed, said pump including a reciprocating piston having two working heads, one in operative relation to the pump chamber and the other in operative relation to a motive chamber; an inlet and non-return valve therefor controlling free low-resistance flow of fluid into said pump chamber; an outlet and non-return valve controlling a relatively high resistance flow of fluid out of said pump chamber; a conduit connecting the motive chamber of the pump with the combustion chamber of a cylinder of the engine whereby at low speeds of the engine the alternating vacuum and high pressure conditions of the engine cylinder produce modified vacuum and high pressure conditions in the motive chamber of the pump and, at high engine speed, produce pulsating pressures higher than atmosphere in the motive cylinder of the pump; a long spring at the pump end of the piston to oppose the expansion strokes and assist the return strokes; and a shorter spring at the motive end of the piston to oppose vacuum strokes and assist expansion strokes.
31. A variable-throttle, variable-speed internal combustion engine in combination with a pump for utilizing the alternating vacuum and high pressure conditions in the combustion chamber of the cylinder of the engine to pump fluids throughout all variations of throttle opening and engine speed, said pump including a reciprocating piston having two working heads, one in operative relation to the pump chamber and the other in operative relation to a motive chamber; an inlet and non-return valve therefor con-

- trolling free low resistance flow of fluid into said pump chamber; an outlet and non-return valve controlling a relatively high resistance flow of fluid out of said pump chamber; a conduit connecting the motive chamber of the pump with the combustion chamber of a cylinder of the engine whereby at low speeds of the engine the alternating vacuum and high pressure conditions of the 10 engine cylinder produce modified vacuum and high pressure conditions in the motive chamber of the pump, and, at high engine speed, produce pulsating pressures higher than atmosphere in the motive cylinder of 15 the pump; a spring permitting reciprocation of said pump piston by alternating pressure and vacuum in the motive chamber of the pump, at low engine speed and automatically compensating for the excess pressure 20 at high speeds when the pressures in the motive chamber of the pump becomes pulsating; and a shorter spring acting in the opposite direction to be compressed on the return strokes and to expand on the expansion 25 strokes of the piston at lower engine speeds when the pressure variations are slow enough to permit the piston to complete a return stroke at each suction stroke of the engine.
- 30 32. In apparatus of the class described, an internal combustion engine in combination with a pump having a pumping element, one face of which is directly connected with the combustion chamber of a cylinder of said engine and actuated by the alternating pressures therein; the other face of said pump element being in operative relation to a pumping chamber provided with suitable inlet and outlet passages and valves; a spring 35 on the pump side of said pumping element compressing on expansion movement of said pumping element and expanding on return movement thereof; and another spring on the motive side of said pumping element, of 40 shorter length and range than said first mentioned spring, for the purpose described.
33. In apparatus of the class described, an internal combustion engine in combination with a pump having a pumping element, one 50 face of which is directly connected with the combustion chamber of a cylinder of said engine and actuated by the alternating pressures therein; the other face of said pump element being in operative relation to a pumping chamber provided with suitable 55 inlet and outlet passages and valves; and springs acting oppositely on said pumping element; and differently for different portions of the range of movement thereof.
- 60 34. In apparatus of the class described, an internal combustion engine in combination with a reservoir and pump; said pump including a piston having one portion in operative relation to a pump chamber, an up- 65 wardly opening conduit and check valve for upward inlet of liquid from the source of supply and an outlet and upwardly opening check valve for outlet of liquid to the interior of said reservoir; and said piston having another portion in operative relation to 70 an expansion space for motive fluid; a conduit connecting said motive space with the combustion space in a cylinder of the engine; said pump chamber, piston and outlet being formed and relatively arranged so as to 75 cause automatic expulsion of all gaseous fluids from said pump chamber through said outlet into the reservoir.
35. In apparatus of the class described, an internal combustion engine in combination with a reservoir and pump; said pump including a pumping element having one portion in operative relation for direct contact with liquid in the pump chamber, an upwardly opening conduit and check valve for 80 inlet of liquid from the source of supply and an outlet and upwardly opening check valve for outlet of liquid to the interior of said reservoir; and said pumping element having another portion in operative relation to an 85 expansion space for motive fluid; a conduit connecting said motive space with the combustion space in a cylinder of the engine; the parts of said pump including pump chamber, outlet and pumping element being 90 formed and relatively arranged so as to cause automatic expulsion of all gaseous fluids from the pump chamber.
36. In apparatus of the class described, an internal combustion engine in combination with a combined reservoir and pump unit; said pump including a pumping element having one portion in operative relation to a pump chamber, a conduit and check valve for inlet of liquid from the source of supply 95 and an outlet and check valve for delivery of liquid to the interior of said reservoir; and said pumping element having another portion in operative relation to an expansion space for motive fluid; a conduit connecting 100 said motive space with the combustion space in a cylinder of the engine; a governing valve for controlling application of pressure through said conduit, and means for controlling said valve by and in accordance 105 with the level of liquid within the reservoir to maintain approximately constant level thereof; said level controlling mechanism being wholly within said reservoir, and its connections of actuating said governing valve 110 being through exteriorly sealed openings which communicate only with the interior of 115 said reservoir.
37. A fuel supply system for internal combustion engines comprising a reservoir 120 from which fuel is supplied to the carburetor by gravity, a passageway between said reservoir and a source of fuel supply, an outlet 125

check valve controlling communication between said passageway and the reservoir, a piston chamber in communication with said passageway, means of communication between the piston chamber and the engine and means whereby the fuel in said reservoir controls such means of communication.

38. A pulsation pump for fuel supply comprising a piston spring actuated in one direction and adapted to be operated by pulsating pressure in the opposite direction, a source of pulsating pressure in communication with the pressure side of said pump piston, and means controlled by liquid fuel delivered by said pump for controlling the

communication between the source of pulsating pressure and the pump.

39. In fuel delivery apparatus a pump including a piston adapted to be exposed on one side to the varying pressure of an internal combustion engine cylinder, and spring pressed in the other direction, a reservoir into which fuel is pumped and means actuated by rise of fuel in said reservoir for controlling connection between the pump and the engine cylinder.

Signed at New York city, in the county of New York and State of New York, this 17th day of October, 1917.

WILLARD IRVING TWOMBLY.
